UNITED STATES PATENT OFFICE

2,650,599

CONTINUOUS PICKLING APPARATUS

Louis T. Campbell, Pittsburgh, Pa., assignor to
United States Steel Corporation, a corporation
of New Jersey

Application December 15, 1948, Serial No. 65,403

3 Claims. (Cl. 134—64)

1

This invention relates to improved apparatus for the continuous pickling of metallic strip, particularly steel strip.

It is the conventional practice to continuously descale hot rolled strip by passing the strip through a series of tanks containing the pickling solution. During its passage through the tanks the strip is supported on rotatable rolls located between the tanks and outside the confines of the tanks. The common practice is to drape the strip over the support rolls, the weight of the unsupported strip between rolls being sufficient to cause it to hang in a catenary and dip into the solution. To avoid corrosion of the bearings and other unprotected portions of their structure the support rolls are located a considerable distance above the level of the pickling solution. To position the strip laterally during its passage through the tanks, side guides are provided at or immediately ahead of each of the support rolls. The maintenance of such guides is difficult.

Owing to the relatively high position of the support rolls and the method of suspension of the strip in the tanks, there is a substantial volume of solution toward the ends of a tank which must be heated and maintained at the required acid concentration while serving no useful purpose. Thus for a required length of immersion, conventional construction results in an unduly long processing line. Sink rolls have been suggested as the remedy for this condition. This expedient, however, has not been successful since their use exaggerates the problems of strip trackage and the cost of their maintenance is excessive.

Since the pickling process involves the use of hot acid solutions, there is a serious problem in fume control. It is the conventional practice to enclose the tanks with a hood which is directly connected to an exhaust fan or fans. The use of support rolls complicates the design of the hood. Openings must be provided for the roll shafts and for inspection and maintenance. Sealing these openings against leaks is practically impossible. The necessarily elevated position of rolls dictates the shape of the hood and results in creating a considerable space between the level of the pickle bath and the underside of the hood. The net result of the combined conditions is that in attempting to prevent pollution of the atmosphere within the pickle house large volumes of air from the building must be moved through the conventional hood system. This not only requires excessively large fans and power, but the

2

movement of large volumes of air over the surface of the bath has a substantial cooling effect on the bath and requires additional heat to maintain the bath at minimum operating temperature. The large surface area of the conventional hood also provides greater area from which heat losses by radiation can take place. This further decreases the efficiency of the process.

Exhausting fumes directly from the surface of the bath has the added disadvantage that large quantities of acid bearing vapors are released into the atmosphere over the pickle house with the result that constant and costly repairs must be made to this and adjacent structures. Moreover, the conventional construction of the pickle tanks and support rolls is such that there are many places at which acid leakage and spillage occurs. This condition shortens the life of the tanks, their supports and foundations.

Accordingly it is an object of the present invention to provide improved apparatus for continuously pickling metallic strip in which the aforementioned objections are overcome.

It is a particular object to provide improved support means for the strip, the use of which permits the provision of an improved cover and an improved fume exhaust system.

These and other objects will be made apparent by the following description when read in conjunction with the attached drawings, in which:

Figures 1 and 1A, when joined together at the dash-dot lines, show a plan view of the tank embodying my invention;

Figures 2 and 2A, when joined together at the dash-dot lines, show a longitudinal sectional view of the tank of Figures 1 and 1A;

Figure 3 is an enlarged sectional view taken on the line III—III of Figure 2;

Figure 4 is an enlarged fragmentary view of the bulkhead of Figure 2;

Figure 5 is a view, partly in section, showing the strip-supporting device;

Figure 6 is an end view of the device of Figure 5; and

Figure 7 is an enlarged sectional view showing the joint between sections of the hood.

Referring more particularly to the drawings which show a specific embodiment of the present invention, a strip S of hot rolled steel is shown entering a pickle tank 1 over a deflector roll 2 which is located just outside the confines of the tank. The tank 1 is preferably a single continuous tank of sufficient length to provide the required immersion time at the maximum speed for which the equipment is designed. The tank

comprises a steel outer shell protected against corrosion from the pickle bath by a rubber lining 3 which in turn is protected against abrasion by the strip and is thermally insulated from the hot pickle solution by a masonry lining 4. The nature and methods of applying the linings to the tank are well-known and therefore are not described here.

The tank is divided into sections or compartments by masonry bulkheads 5. This facilitates maintenance and permits local repairs to the lining without emptying the whole tank. Located over each of the bulkheads 5 is a strip-supporting device 6 formed of a cylindrical rubber roll body 7 secured to a square non-rotatable shaft 8 having a rubber covering over its ends which extend beyond the body 7. The square shafts 8 of the supports 6 rest in pockets 9 built into the brick lining of the tank. The vertical position of the pockets is such that the underside of the cylindrical center portion of the supports 6 is approximately at the liquid level of the pickling solution in the tank. The strip S passes over each of the supports 6 in turn and is suspended in a catenary-like loop between adjacent supports. The weight of the unsupported length of strip between supports 6 is sufficient to maintain this catenary-like shape while the strip is being pulled through the tank. To prevent the strip from resting on the bottom of the tank and thus being subjected to unequal pickling conditions, rubber-covered skid supports 10 are provided at intervals along the bottom of the tank. After the strip S passes over the last of the supports 6 located adjacent the last bulkhead, it passes under deflector rolls 11 and 12 and hence out of the tank through squeegee rolls 13. That section of the tank in which rolls 11 and 12 are located comprises a rinse compartment. The deflector rolls 11 and 12 in the rinse compartment serve to depress the strip below the surface of the rinse water.

Substantially flat sectional removable covers 14 are provided to confine substantially all fumes and steam into the space immediately above the pickle solution. The covers 14 rest upon a gasket 15 located along the top surfaces of the masonry lining 4. The covers are protected against corrosion by a rubber lining 16. An overlapping joint 17 is provided between sections as shown in Figure 7 to form a seal.

Located along both sides of the tank are inverted L-shaped ducts 18. The ends of the horizontal legs of the ducts 18 are open and form a substantially continuous slot 19 through which any fumes or steam which might escape from under the covers 14 are withdrawn. The openings 19 are provided with adjustable orifice plates 20 whereby the velocity of air entering the ducts can be regulated and equal suction maintained along the length of the ducts. The duct orifice 19 is located as close as possible to the joint made by the cover 14 and the gasket 15 at the top of the tank. The collector ducts 18 are preferably made in sections of some convenient length and each section connected through a downcomer 21 and suitable fittings to a common manifold 22, hence to a fan or blower 23, the exhaust side of which is connected to a stack 24 which terminates outside the building housing the equipment.

All necessary openings into the interior of the pickling tank, such as for the passage of steam pipes for heating, acid supply lines, etc., are made as near as possible to the edge of the cover. In this manner any leaks around such openings oc-

cur in the vicinity at which the exhaust system is most efficient.

The pickling tank of the present invention may be supported on a substructure consisting of the 5 equally spaced transverse beams 26 which rest upon the longitudinal beams 27 which in turn are supported at appropriate intervals by concrete or masonry piers not shown. The support structure for the tank is preferably that shown in my co-pending application, Serial No. 64,558, filed December 10, 1948. The side walls of the tank 4 are stiffened by the buck-stays 25.

If the progress of the strip through the tank is stopped for any appreciable time, there is danger of the strip S being overpickled or otherwise damaged by the action of the acid. To avoid such damage, devices 28 can be provided which include movable arms extending through the covers 14 whereby the strip can be raised out of contact with the acid.

The nature and form of equipment necessary for handling the strip S into and out of the pickling section described above is well-known and therefore has not been described here. Suitable equipment for performing these operations is shown in the United States Patent to Wean et al. No. 2,196,600.

In operation, the strip S passes through the successive pickling compartments where its surfaces are freed of oxide by the action of the acid solution and then through the rinse chamber where the freshly pickled surface is washed with cold water. Fresh acid may be introduced into the system at a point near the end of the last pickling compartment. The addition of fresh acid is preferably continuous, the rate being regulated to maintain a desired uniform concentration in the last compartment. Water losses may be made up by permitting a controlled portion of the wash water in the rinse compartment to overflow into the last pickling compartment. In this manner a portion of the acid solution lost by drag-out on the surface of the strip may also be recovered. The pickling solution flows from the last compartment towards the first so that the strip is subjected to cleaner and stronger solution as it progresses through the tank. The waste pickle liquor is preferably removed near the entry end of the first compartment where it is allowed to overflow through a standpipe or equivalent liquid-level-maintaining arrangement to a waste acid disposal system. The interchange of solution between compartments may be accomplished in several ways, a satisfactory way being to regulate the height and shape of the bulkheads 5 so as to form a weir. The rinse compartment is provided with a standpipe or similar liquid-level-maintaining arrangement which is connected to a drain. Following rinsing, the strip passes to the pinch rolls 13 which remove excess rinse water. The strip may then be further rinsed or otherwise processed, dried and coiled.

The pickling solution must be maintained hot and this may be accomplished by any of several means. A means which has proven very satisfactory is Venturi-type steam injectors which not only produce the necessary heating but also a high degree of turbulence within the bath which contributes to the efficiency and uniformity of pickling action.

As previously mentioned, the steam pipes enter the tank through the cover at a point as close as possible to the junction of the cover with the 75 top of the tank. Water pipes and acid supply

pipes also enter the tank through the cover at this general location.

The steam and acid fumes which were involved during the pickling are confined within the tank by the substantially flat covers 14. Any steam or acid fumes which may leak at this junction or around the openings in the cover for the admission of steam, acid or water lines are drawn into the ducts 13 and conducted out of the building through the exhaust system previously described. The exhaust system in the present invention is not directly connected to the tank cover as is the case in conventional practice. Thus the removal of fumes is accomplished without drawing air through the pickling tank itself. This permits the maintenance of higher pickling bath temperatures with the use of less heat and, for a given length of pickling bath, markedly increases the production capacity of the equipment.

The use of substantially flat covers and an exhaust system which is not directly connected thereto is made possible largely by the improved strip-supporting devices 6. The use of a single continuous tank is also largely attributable to the improved devices 6. The strip-supporting devices 6 do not revolve as do conventional support rollers; the strip merely skids over their rubber-covered surfaces which are maintained lubricated by the pickling solution carried to them by the strip as it passes from one compartment to the next. Since the supports 6 do not revolve, all parts are readily protected from the acid solution by rubber covering. The fact that they do not have to rotate reduces the size of support required. The new supports 6 can therefore be located entirely inside the tank and very close to the solution level therein. Thus dead space at the ends of the tank is considerably reduced and the length of the tank can be materially shortened. Furthermore, the need for side guides within the tank is eliminated by the use of the improved supports 6. It is sufficient to laterally position the strip only at it enters the tank.

The cylindrical form of the support 6 is merely a preferred shape which permits a worn supporting surface to be replaced by simply lifting the support out of its normal position, revolving it 90° and reinstalling. The cylindrical form of the support 6, therefore, provides four supporting surfaces which can be used before the support must be replaced or repaired.

Although I have illustrated and described a preferred embodiment of the invention, it will be recognized that changes in the details and arrangement disclosed may be made without departing from the spirit of the invention or the scope of the appended claims.

I claim:

1. In apparatus for the pickling of continuous metallic strip, the combination which includes a tank for containing the pickling solution, a

substantially flat removable cover on said tank, a non-revolving strip support located entirely within the confines of said tank above the solution level therein and below said cover, said non-revolving support comprising a cylindrical body of a corrosion-resistant material mounted on a square shaft, the ends of said shaft extending beyond said cylindrical body and being protected by a covering of a corrosion-resistant material, shaft receiving recesses in the walls of said tank for engaging said shaft to maintain the support in fixed position, and a fume exhaust system, said exhaust system including horizontally disposed ducts extending substantially the length of and along both sides of said covered tank, said ducts having a substantially continuous fume receiving opening adjacent the juncture of said cover with said tank.

2. In apparatus for the pickling of continuous metallic strip, the combination which includes a tank for containing the pickling solution, a substantially flat removable cover on said tank, a stationary strip support having a smooth convex upper surface, said support positioned entirely within the confines of said tank above the solution level therein and below said cover, and a fume exhaust system separate from said tank, said exhaust system including horizontally disposed ducts extending substantially the length of and along both sides of said tank and characterized by adjustable and substantially continuous fume receiving orifices located adjacent the joint between the cover and the top of said tank.

3. In apparatus for the pickling of continuous metallic strip, the combination which includes a tank for containing the pickling solution, a non-revolving strip support located entirely within the confines of said tank above the solution level line, said non-revolving support comprising a cylindrical body and a square shaft, the outer surfaces of said shaft and said cylindrical body being of a corrosion-resistant material, and shaft receiving recesses formed in the tank to engage said shaft and maintain the support in fixed position.

LOUIS T. CAMPBELL.
